UNITED STATES PATENT OFFICE

GEORGE G. GOING, OF MIDDLETOWN, CONNECTICUT, ASSIGNOR, BY MESNE ASSIGNMENTS,
TO REMINGTON TYPEWRITER COMPANY, A CORPORATION OF NEW YORK

TYPEWRITING MACHINE

Application filed June 25, 1927. Serial No. 201,429.

My invention relates to paper feed and controlling devices for typewriting and like machines.

One of the main objects of my invention, 5 generally stated, is to provide improved and highly efficient devices of the character specified, which are simple in construction, easy to assemble, and inexpensive to manufacture.

A further object of my invention is to provide means for directing the leading end of a 10 work sheet beneath feed rollers located beyond the printing line, without the necessity of adjusting the paper fingers to coact with the work sheet, and without the necessity of 15 throwing such feed rollers off and introducing the leading end of the work sheet beneath them and again restoring the feed rollers to effective position.

To the above and other ends which will 20 hereinafter appear, my invention consists in the features of construction, arrangements of parts and combinations of devices set forth in the following specification and particularly pointed out in the appended claims.

25 In the accompanying drawings, wherein like reference characters indicate corresponding parts in the different views:

Figure 1 is a front view of a carriage of a typewriting machine equipped with the 30 devices of my invention.

Figure 2 is an enlarged, detail, longitudinal sectional view of one of the feed rollers mounted in place on its supporting rod, the section being taken on the line 2—2 of Fig. 35 1 and looking in the direction of the arrows at said line.

Figure 3 is an enlarged, detail, transverse sectional view of the same, taken on the line 3—3 of Fig. 2 and looking in the direction 40 of the arrows at said line.

Figure 4 is an enlarged, detail, perspective view of one of the adjustable roller supporting sleeves, shown detached.

Figure 5 is an enlarged, fragmentary, vertical, fore-and-aft, sectional view of the carriage, taken on the line 5—5 of Fig. 1 and looking in the direction of the arrows at said line.

Figure 6 is a detail, fragmentary, sectional 50 view showing the supporting rod and one of

the carrying arms therefor, the section being taken on the line 6—6 of Fig. 1 and looking in the direction of the arrows at said line.

Figure 7 is a detail, fragmentary, perspective view of the central deflector shown 55 mounted on its supporting rod.

Figure 8 is an enlarged, detail, sectional view showing one of the paper fingers on its supporting rod, the section being taken on the line 8—8 of Fig. 10 and looking in the direction of the arrows at said line.

Figure 9 is a detail perspective view of a paper finger, its supporting and surrounding sleeves and the supporting rod, the view showing the parts detached and as they appear when they are about to be assembled.

Figure 10 is an enlarged, detail, transverse, sectional view taken through one of the paper fingers and its supporting rod, the section being taken on the line 10—10 of Fig. 8 and 70 looking in the direction of the arrows at said line.

I have shown my invention embodied in the present instance, in the carriage of a No. 6 Remington-Noiseless machine in which the 75 invention may be readily included without modifying, or materially modifying, other structural features of said machine. It should be understood, however, that the invention is not restricted to use in such machine, but is applicable to and may be employed in typewriting or like machines generally.

In said Remington-Noiseless machine the 85 carriage comprises a traverse bar 1 to which are connected end plates 2 provided with bearings to support a cylindrical platen 3. The traverse bar 1 is supported by roller bearings in the usual manner to travel from side to side of the machine.

A paper apron 4, main feed rollers 5 and 6, and supporting rod 7 are mounted in the manner indicated in my application Sr. No. 180,202 filed April 1, 1927, and only so much 95 of the details of such construction are shown in the drawings of this case as are necessary to arrive at an understanding of the present invention. In the present instance the supporting rod 7 which is arranged above or beyond the printing line has one or more flat- 100

tened sides, being preferably angular in cross section. At its ends the rod passes through corresponding openings in depending ears 8 (see Fig. 6) on upstanding supporting arms 9 to which the rod is secured by screws 10. Each supporting arm is formed with an upstanding finger piece 11 and is pivoted at its lower end, as indicated at 12, to the lower end of a depending link 13. The upper end of each link 13 is pivoted at 14 to an end plate 2. Each arm 9 has a rearward extension 15 to which one end of a coiled contractile spring 16 is attached, the other end of each spring being connected to an arm or plate 17 adjustably held in place on the carriage by a binding screw 18. The force of the springs 16 is exerted through the supporting arms against the rod 7 to hold the paper fingers, feed rollers and deflector carried thereby in normal effective position as shown in Figs. 1 and 5, and with an equally applied pressure at opposite ends of the rod, as will hereinafter appear.

Various paper feed or controlling devices are carried by and adjustable along the supporting rod 7, as will now be described.

A pair of paper fingers 19, preferably made of sheet metal and each provided with upstanding ears 20, are apertured at 21. The walls of each aperture are shaped to correspond to the cross section of the rod 7 which extends through said apertures and supports the paper fingers against turning movement thereon, although each finger is free to be independently adjusted along the rod. Each paper finger is curved to conform substantially to the surface of the platen; is interposed between the supporting rod and the platen and extends down from the rod located above or beyond the printing line. Each finger crosses the printing line and overlaps the forward edge 4^a of the paper apron below the printing line. In this manner work sheet *a*, of a width to pass beneath said fingers 19 without readjustment of the latter, will have its leading end guided and directed by said fingers as it advances from the paper apron and until it passes beneath and beyond the supporting rod 7 and the parts carried thereby.

In the present instance I have provided simple and effective detent devices associated with each paper finger and by which it is held against accidental displacement from the position to which it may be individually adjusted along the rod 7. Such detent devices comprise a metal sleeve 22 that fits on and surrounds the rod 7. Punched inwardly from this sleeve is a spring detent finger 23 that extends longitudinally of the sleeve 22 and the rod 7. This finger at one end 24 is formed integral with the sleeve and at its opposite free end portion extends inward and bears with a spring pressure on one of the flat sides of the rod 7. This sleeve 22 is of a length

that corresponds to the distance between the ears 20 of the companion paper finger. The sleeve being mounted on the rod intermediate the ears of the associated paper finger will coact therewith to prevent it from being accidentally displaced along the rod from the position to which it is adjusted. I prefer to loosely surround each sleeve 22 with a second sleeve 25 of corresponding length which gives a more finished appearance to the structure and also provides a convenient finger piece by which the associated paper finger may be adjusted along the rod 7. The surface of the sleeve 25 may be knurled on its surface as indicated at 26, to provide a more effective finger piece for the purpose described.

Intermediate the paper fingers 19 and separate and distinct therefrom is a pair of paper feed rollers 27 mounted on and coaxially of the supporting rod 7. Each of these feed rollers is preferably constructed and mounted as follows:—The outer rubber sheath 28 is fixed on tubular metal sleeve, shell or core 29. This core surrounds and turns freely on a cylindrical supporting sleeve 30, shown detached in Fig. 4. One end of the sleeve 30 is provided with a flange 31 which overlaps one end of the sleeve 29 and prevents relative axial movement between the two in one direction. After the two sleeves 29 and 30 are assembled a second flange 32 is formed at the opposite end of the sleeve 30 to overlap the end of and coact with the sleeve 29, thus preventing any relative axial movement between the two sleeves. The sleeve 30 has a tongue or finger 33 punched inwardly therefrom which in form, purpose and effect corresponds to the fingers 23 hereinbefore described. The free end portion of the finger 33 bearing on a flat side of the rod 7 acts as a spring detent to hold the companion feed roller in the position to which it is adjusted along the rod and also holds the sleeve 30 against turning movement while the feed roller supported on said sleeve is free to turn thereon.

It will be understood that a work sheet *a* fed forward under the control of the paper fingers will be directed beneath the feed rollers 27 and the supporting rod 7 without necessitating a forward shifting of the rod with the parts carried thereby to introduce the leading end portion of the work sheet between such parts and the platen, as is often required in other structures.

When a work sheet or card is employed, such as is indicated at *b*, that is of a width less than the distance between the paper fingers, it has been customary heretofore to adjust the paper fingers towards each other until they overlap the side edge portions of such work sheet and then proceed with the writing. After completing the writing the operator may then desire to again employ a wider work sheet such as *a*. This would require a readjustment of the paper fingers

back to their original positions near the side margins of the sheet in order to prevent the fingers from covering a portion of the sheet where writing is to appear, and in order to 5 avoid bringing the paper fingers in the path of the types during the writing of each line. By my present invention I avoid this repeated back and forth adjustment when the occasional writing of a comparatively narrow work 10 sheet or card is required during the writing of wider sheets. The devices of the present invention readily lend themselves to this desired end, inasmuch as the feed rollers 27 may be adjusted independently of the paper fingers. This enables the paper feed rollers to 15 be located at any desired points along the supporting rod intermediate the paper fingers and to properly coat with a work sheet or card however narrow it may be, and even 20 though the paper fingers do not coat therewith but remain in the positions to which they are adjusted to coat with the wider work sheets. While the feed rollers 27 will thus coat with the narrow work sheets, they also, 25 without readjustment, will coat with the wider work sheets that pass beneath the paper fingers.

In order that a narrow work sheet or card 25 may have its leading end fed beneath the feed rollers 27 and rod 7 while they remain in normal position, I have provided a special deflector which will now be described.

This deflector is preferably made of sheet metal bent at one end to form a sleeve 34 30 which is angular in cross section. This sleeve receives the correspondingly shaped supporting rod 7 and is adjustable along the latter although it is fixed against turning movement on the rod. A spring tongue or finger 35 is punched in from the sleeve and bears at its free end portion with a spring pressure 35 against a flat side of the supporting rod. The construction, purpose and effect of the finger 35 are the same as the fingers 23 and 33, here- 40 inbefore described. That is to say, the finger 35 acts as a spring detent which coacts with supporting rod 7 to hold the sleeve 34 and the parts carried thereby against accidental displacement from the position to which they are 50 adjusted along said rod.

Formed as a continuation of one of the sides of the sleeve 34 is a depending plate-like extension 36 that projects from the lower side of the rod forward and downward 55 in such position that the leading end of a work sheet uncontrolled by the paper fingers may coat therewith and be deflected thereby into the bight between the feed rollers 27 and the platen. Being thus engaged between 60 said feed rollers and the platen the sheet will be fed forward under the feed rollers and the supporting rod 7 without necessitating a forward displacement of the rod 7 and the parts carried thereby and a placing of the 65 sheet beneath the same, and without necessi-

tating an adjustment of the paper fingers to coat with such narrow sheet. In practice I prefer to locate the deflector just described intermediate the feed rollers 27 and preferably about midway in the length of the rod 7 where it will not interfere with the ready adjustment of the feed rollers 27 and paper fingers 19. However, the deflector, as well as said feed rollers and paper fingers, is individually adjustable so that the parts may be adjusted to assume various relations. For example, the parts may be adjusted so that a comparatively narrow card may be controlled and written from an off-centered position corresponding to that near which one side of either a centered or off-centered comparatively wide work sheet is controlled. 75

It will be understood that the construction is such that the parts may be readily assembled on the supporting rod 7 when the latter is detached from its supporting arms 9, by merely slipping the sleeves 22, 30 and 34 with the parts carried thereby over an end of the rod in the order shown and then attaching the rod to the arms 9 by the screws 10. 80

From the foregoing it will be understood that I have provided simple, inexpensive and effective means for feeding and controlling work sheets of different widths and with the aid of which repeated adjustments, re-arrangements, or releasing of the parts with consequent delays and extra work incident thereto are avoided. 95

As pointed out in my hereinbefore mentioned previously filed application the mounting of the supporting rod 7 on the links or arms 9 and 13, and applying the force of the springs 16 thereto in the manner shown enables the rod to receive a limited canting movement out of parallelism with the axis of the platen as well as to remain in parallelism therewith. This results in applying the paper feed devices near the opposite ends of the rod against the platen or the paper thereon with substantially equal pressure and effecting a straight feed of the paper under varying conditions. 100

Various changes may be made in the construction, and parts thereof may be employed, without others, without departing from my invention as it is defined in the accompanying claims. 115

What I claim as new and desire to secure by Letters Patent, is:—

1. The combination of a supporting rod, a paper controlling device, and means associated therewith for retaining said device against accidental displacement from any position to which it may be adjusted along said rod, said means comprising a sleeve that surrounds said rod and has a punched-in integral spring finger that bears against said rod and thus holds the sleeve and associated paper controlling device in adjusted position. 125

2. The combination of a supporting rod, a sleeve that surrounds said rod and has a punched-in integral contact finger that bears against said rod to hold the sleeve in any position to which it may be adjusted along said rod, a second sleeve surrounding said first mentioned sleeve and free to turn thereon but covering the opening in the first mentioned sleeve left by the punched-in contact finger, and a paper controlling device associated with said sleeves and controlled in its position of adjustment along said rod by said sleeves.
3. The combination of a supporting rod having one or more flat sides, a paper finger having ears with openings therein that conform to the cross section of said rod so that the paper finger is held against turning movement on said rod, and a sleeve that surrounds said rod intermediate said ears, said sleeve having an inwardly extending contact finger that bears against said rod to hold it and the paper finger in the position to which they may be adjusted together along said rod.
4. The combination of a supporting rod having one or more flat sides, a paper finger having ears with openings therein that conform to the cross section of said rod so that the paper finger is held against turning movement on said rod, a sleeve that surrounds said rod intermediate said ears, said sleeve having a contact finger that bears against said rod to hold the sleeve and paper finger in the position to which they may be adjusted together along said rod, and a second knurled sleeve that surrounds said first mentioned sleeve and constitutes a finger piece by which the knurled sleeve and associated parts may be adjusted together along said rod.
5. The combination of a supporting rod, a paper controlling device, and means associated therewith for retaining said device against accidental displacement from any position to which it may be adjusted along said rod, said means comprising a sleeve that surrounds said rod and having an integral spring finger that is struck up from and extends longitudinally of the sleeve and is united thereto at one end and bears at its other free end portion inwardly against said rod and thus provides a friction detent that holds said sleeve and the associated paper controlling device in the position to which they are adjusted along said rod.
6. The combination of a supporting rod, and a work sheet deflector for guiding a work sheet to and beneath said rod, said deflector being formed from a single piece of sheet metal with a sleeve at one end which surrounds said rod, a detent finger punched in from said sleeve and coacting with said rod to hold the deflector in its adjusted position along said rod, and a depending plate-like deflecting member extending from said sleeve and cooperative with the leading end of a

work sheet to direct it to and beneath said rod.

7. The combination of a cylindrical platen, a supporting rod arranged above the platen, means for mounting said rod for movement into and out of parallelism with the surface of the platen but for holding it against turning movement around its longitudinal axis, means for spring impelling the rod towards the platen, paper fingers depending from said rod across the printing line and individually and adjustable along said rod, individually adjustable paper feed rollers separate from and intermediate said paper fingers, said feed rollers being coaxial with said rod, and a paper deflector mounted for adjustment along said rod intermediate said feed rollers but fixed against turning movement on said rod, said deflector at all times standing away from and out of contact with the platen to coact with work sheets and direct them beneath said feed rollers and rod.

Signed at Middletown, in the county of Middlesex and State of Connecticut this 23rd day of June, A. D. 1927.

GEORGE G. GOING.
